UNITED STATES PATENT OFFICE.

VINCENT LASBURY, OF GRIGGSVILLE, ILLINOIS.

CAMP STOVE.

1,420,043.

Specification of Letters Patent. Patented June 20, 1922.

Application filed February 5, 1921. Serial No. 442,867.

To all whom it may concern:

Be it known that I, VINCENT LASBURY, a citizen of the United States, residing at Griggsville, in the county of Pike and State 5 of Illinois, have invented certain new and useful Improvements in Camp Stoves, of which the following is a specification, reference being had to the accompanying drawings, and to the reference characters marked 10 thereon, which form a part of this specification.

This invention relates to portable, knock-down camp stoves.

One of the objects of my invention is to 15 make a stove for campers' use, which is not only easy to take apart and pack for shipment, but which is of such simple construction as to require no expert experience in putting the parts together for use.

20 Another object of my invention is to fabricate the several sections in such manner as to give the greatest amount of strength and greatest resistance to warping consistent with the use of thin gauge metal.

25 Another object of the invention is to provide a simple and efficient construction as cheaply as possible and one which will not readily get out of order and require repairs.

The advantages of my invention will be 30 more readily understood as I proceed with my specification; the invention consisting in the devices and combinations of devices described, illustrated and pointed out in the appended claims.

35 In the drawings:

Fig. 1 illustrates in perspective view, my improved camp stove.

Fig. 2 is a bottom plan view of the removable lid for the stove top.

40 Fig. 3 is an inside view of a detail of the end wall showing the fire door in position,—the same being taken upon the line 3—3 of Fig. 4.

45 Fig. 4 is a vertical, longitudinal sectional view taken upon the plane of the dotted line 4—4 of Fig. 5.

Fig. 5 is a transverse, vertical sectional view taken upon the plane of the line 5—5 of Fig. 4.

50 Fig. 6 is a view in perspective, showing the method of uniting the rear end wall with the two side walls.

Fig. 7 is a bottom plan view of the top wall of the stove.

Fig. 8 is a detail sectional view, enlarged, 55 of a portion of the stove pipe opening, to more clearly show the connection between the stove pipe and the stove top.

In the drawing, A represents the stove as a whole, as shown in Fig. 1. This stove 60 consists of a front end wall B, a rear end wall C, two side walls D, D, a telescopic pipe E, and a removable lid F for the cover or top of the stove G. The two side walls are of similar construction, but made "right" 65 and "left." One only will be described.

A metal plate 1 of the desired dimensions, rectangular in shape, is provided at its lower end with a relatively stiff rod 2, about which the lower edge of the metal 1 is wrapped, 70 so as to form the bead or support 3, which constitutes the bottom edge of the side wall D and rests upon the ground when the stove is in use. The top edge of the wall D is similarly provided with a rod 4, enclosed 75 within the bent over edge of the sheet metal 1 to form a bead 5. The two ends are reinforced by vertical plates placed on both sides of the sheet metal plate 1, so as to form a vertical longitudinal groove into 80 which the flanges of the end wall C will fit. This construction is shown in Fig. 6, as follows: the edge of the sheet metal 1 is doubled upon itself as shown at 6. Vertical 85 strengthening plates 7, 7, are placed one on each side of the thickened edge 6 and secured thereto by rivets 8 or other suitable means, thus forming between said strengthening plates 7 the recess 9. At the lower end 90 of each plate D is an angle bar 10, riveted at the side of the outer plate 7 with its short member extending beyond and bent over in front of the end edges of the strengthening plates 7, as shown at 11. This angle bar 10, 11, thus forms a locking member 95 at the lower corner of the wall D to secure and lock the end wall in position.

The end wall C is strengthened at its upper and lower margins by having the metal bent upon itself, as shown at 13, 14 while at 100 each margin of the end wall C, the metal is simply turned at right angles to form guide and locking flanges 15. These flanges 15 are adapted to fit within the recess 9 and between the plates 7, 7 of the side walls D, as 105 indicated in the dotted line of Fig. 4.

The front wall B, so far as its top and bottom edges are concerned, and its side

margins, is similarly constructed and will not therefore be further described in this particular.

It will be understood that when the two side walls D, D, are placed in parallel relation, standing vertically upon their beaded edges 3, these may be united to form a rectangularly shaped box by first engaging the lower ends of the flanges 15 of the end wall 10 C in the recess 9, and then pushing the entire plate C vertically downward until its lower end is firmly locked by the projecting part 11 on each side wall D. The front wall B is similarly united to the forward margins of the side walls D, D. These four parts are then held firmly together by placing on the top the top wall G.

This top G is provided with a downwardly projecting flange 16, formed by bending the 20 end margins and the two side margins, and interlocking them at their overlapping, meeting edges, by rivets 17. This flange 16, as clearly shown in Figs. 1, 4 and 5 will surround the upper margins of the end walls B, 25 C, and the two side walls D, and completely hold the stove structure in firm relationship.

Near the front end of the top G, that is near the wall B, I make a lid opening which is covered by the lid F, and near the rear 30 end, I make a smoke opening leading to the stove pipe E. This smoke opening is preferably rectangular in shape, as shown. The edge of this opening is protected by a binding which constitutes a flanged border for the pipe E. This binding is made by bending a piece of metal 18 upon itself as shown at 19, to constitute the flange proper. The other edge of the metal 18 is bent outwardly at 20, on each of the four sides of the opening. The several parts 20, 20, thus press against the under side of the top G and are riveted thereto by rivets 21. The opening for the stove lid on the top G is made by cutting an aperture in the top G of a diameter somewhat less than the intended diameter of the finished opening, then slitting the margin somewhat to form between the slits a series of circumferentially arranged lips 22. These lips 22 are bent inwardly so as to 45 rest against the under surface of the top G, as clearly shown in Fig. 7. Thus the opening for the lid is substantially circumferential in shape, and is strengthened and defined by this double thickness of metal.

The lid F is of a diameter slightly in excess of the lid opening. It also is made of thin sheet metal, but is strengthened by a plate 23 secured thereto by rivets 24. The diameter of this strengthening plate is substantially that of the interior diameter of the lid opening in the top G. The strengthening plate 23 is provided with transverse ribs 25, 25, formed by fluting or bending the metal of the plate 23. Thus it will be clearly understood that the metal plate 23 resting

within the opening in the top G, prevents improper shifting of the lid F with respect to the top G.

As a matter of convenience and economy of space it will be noted that the lid F and the opening that it covers are located in the front end of the stove, that the smoke opening and pipe are not only located at the back of the stove, but near one side of the top G, thereby affording the maximum space 75 on the top G for cooking utensils.

In order to strengthen the top G to sustain the necessary weight that may be placed upon it in the cooking operation, and also to prevent the metal of which it is composed 80 from warping, I use two strengthening ribs 26, 27. The rib 26 is secured by rivets 28 transversely of the under side of the top G and substantially across its central portion. It is fluted as clearly shown at 29. The 85 strengthening rib 27 is similarly secured by rivets 30 in such position as to run diagonally from one corner of the under side of the top G toward the front and near the strengthening rib 26. This rib 27 is likewise fluted, as shown at 31. The rivets used are flat top rivets as shown, so that the surface of the top G is substantially flat.

While the two side walls D, D, are strengthened by the rods 2 and 4, yet the intermediate sheet metal is liable to warp to some extent and therefore I have found it desirable to place on the inside of each of the walls D slightly above the center thereof, a strengthening rib 32, secured to the 95 wall D by rivets 33. Each of the ribs 32 is centrally bent or fluted as indicated at 34. This makes a very strong construction.

The front wall B of the stove is provided with a sliding fuel door H which moves 105 from side to side in top and bottom guideways, the lower guideway being indicated at 35 and the upper one at 36. These guideways are parallel to each other and extend from side to side of the wall. A suitable handle 37 is riveted to the door H.

The door opening is strengthened and protected by having the sheet metal slit to form lugs or lips 38 bent outwardly from the door opening so as to lie flat against 115 the inside of the end wall B, to which said flaps 38 are riveted at 39. The lower flap which I have designated at 40 however, is not riveted, but is merely bent over the double edge 41 of the lower margin of the 120 end wall B. This makes a very strong construction.

A lug 42 is provided for the door H to afford a stop to limit the movement of the door. A suitable handle opening 43 for the 125 lid F is provided to afford convenient access for a lid lifter.

It will be noted that the stove pipe E is made in telescopic sections, the lower section 44 being provided with a strengthening 130

flange 45 bent to form a shoulder 46. This shoulder 46 rests upon the top margin of the strengthening rib 18, clearly shown in Figs. 4 and 8. The other sections, one of which is indicated in Fig. 1 at 47, are merely rectangular devices that fit within each other in a familiar manner. Thus I may have a pipe as long as is necessary to maintain the proper draft in the stove, while at the same time, a pipe which is collapsible and may be conveniently packed.

49 is a wire or metal rod which is inclosed preferably within the lips 22 to form additional strength to the opening in the stove top, which is usually a weak point in a sheet metal stove. The wire adds stiffness to the metal at this point.

In shipping the stove, I remove the stove pipe E and lid F, turn the stove upside down so as to rest upon the top G, pack the lid and stove pipe therein, together with cooking utensils, etc., and tie the whole together for shipment in that form. More often, however, the entire stove will be taken apart and packed and shipped flat. When thus taken apart, the stove will consist of six flat pieces and the telescopic stove pipe E, thus occupying a minimum of space for shipping and handling purposes.

30 I claim as my invention:

1. A knock-down, sheet metal camp stove comprising two side members, two end members, the height of the latter being equal to the transverse dimension or width of the former, complemental means on the end and side members for engaging said members to form a rectangular shaped stove open at its top and bottom, means on the side members for locking the lower margins of the end members in position with respect to the lower part of the side members, a removable top provided with a downwardly projecting marginal flange adapted to embrace the top margins of the side and end members and securely hold the entire structure in operative position.

2. A knock-down, sheet metal camp stove comprising two side members, two end members, the height of the latter being equal to the transverse dimension or width of the former, complemental means on the end and side members for engaging said members to form a rectangular shaped stove open at its top and bottom, means for locking the lower margins of the end members in position with respect to the lower part of the side members, a top provided with a downwardly projecting marginal flange adapted to embrace the top margins of the side and end members and securely hold the entire structure in operative position, said locking means comprising an L-shaped strip at each end of each side member adapted to embrace the lower part of each end member.

3. A knock-down, sheet metal camp stove comprising two side members, two end members, the height of the latter being equal to the transverse dimension or width of the former, complemental means 70 on the end and side members for engaging said members to form a rectangular shaped stove open at its top and bottom, means for locking the lower margins of the end members in position with respect to the 75 lower part of the side members, a top provided with a downwardly projecting marginal flange adapted to embrace the top margins of the side and end members and securely hold the entire structure in operative 80 position, said complemental means including side marginal flanges upon the end members and spaced strengthening strips on the edges of the side members.

4. A knock-down, sheet metal camp 85 stove comprising two side members, two end members, a top member having a plurality of openings therethrough, a stove pipe extending over one of said openings, a fuel door in one of the end members, the 90 lower edge of each side member being formed into a bead embracing a longitudinally extending metal rod and the lower edge of each end member being reenforced by bending the sheet metal upon itself, a 95 pair of strengthening strips embracing each end of the side members, a flange on each side of the two end members adapted to slide into the space between the pair of strengthening strips on the adjacent end 100 of the side members, an over-hanging angle member on the lower part of each end of each side member adapted to hold the end member flanges locked between said strengthening strips, and a downwardly projecting flange on the margins of the top 105 adapted to embrace the upper margins of the side and end members and lock them together.

5. In a camp stove of the class described, 110 sheet metal side members rectangular in shape, the top and bottom longitudinal margins of each being bent to form a round hollow bead, a metal rod in each bead, each of said side members being reinforced by 115 a pair of spaced, relatively heavy, flat metal strips secured transversely of its front and rear margins, and by a fluted sheet metal strengthening strip positioned longitudinally of the side member with its ends abutting the side margins of said flat metal strips.

6. In a camp stove of the class described, 120 sheet metal side members rectangular in shape, the top and bottom longitudinal margins of each being bent to form a round hollow bead, a metal rod in each bead, each side member being reinforced by a pair of spaced, relatively heavy, flat metal strips secured transversely of the front and rear 130

5 margins, and by a fluted sheet metal strengthening strip positioned longitudinally thereof slightly above its median line with its ends abutting the side margins of said flat metal strips.

In testimony that I claim the foregoing as my invention I affix my signature, in the

presence of two witnesses, this 1st day of February, 1921.

VINCENT LASBURY.
